UNITED STATES PATENT OFFICE.

MINOT K. HOLMES, OF MUNCIE, INDIANA, ASSIGNOR TO HEMINGRAY GLASS COMPANY
OF MUNCIE, INDIANA, A CORPORATION OF KENTUCKY.

RAIN-GUARD FOR INSULATORS.

1,088,278.

Specification of Letters Patent. Patented Feb. 24, 1914.

Application filed April 16, 1913. Serial No. 761,644.

To all whom it may concern:

Be it known that I, MINOT K. HOLMES, a citizen of the United States, residing at Muncie, in the county of Delaware and State of Indiana, have invented a new and useful Rain-Guard for Insulators, of which the following is a specification:

The object of my invention is to produce a guard which may be readily applied to ordinary glass insulators to protect the inner surfaces of their petticoats from water splashed upwardly from the support.

The accompanying drawings illustrate my invention.

Figure 1 is an axial section of my guard in place upon a common insulator, and Fig. 2 is a perspective view of the guard.

In the drawings 10 indicates the main plate or floor of the guard preferably slightly cupped toward the center opening 11 which is preferably guarded by a downwardly and outwardly turned lip 12. Floor 10 is conveniently turned up at its circumference into a vertical flange 13 of a diameter slightly larger than the largest diameter of the insulator 14, and rising from this flange are several spring fingers 15, which are preferably curved to approximate the curvature of the insulator, both for appearance and for added stiffness, and the free ends of these fingers are pressed inwardly so as to normally lie closer to the axis of the guard than the adjacent portions of the insulator.

The guard may be readily sprung over the insulator and its floor will thoroughly guard the petticoats of the insulator from splashing water. All water flowing downwardly on the outside of the insulator will flow over

floor 10 and out through opening 11 running back or outwardly on lips 12 so that any splashing of this water will be at such an angle as not to reenter opening 11.

I claim as my invention:

1. As an insulator petticoat-guard, a centrally perforated plate downwardly inclined toward its perforation with a downwardly-and-outwardly turned drip-lip bounding said perforation, and with a plurality of upwardly-and-inwardly projecting spring fingers formed to embrace the body of an insulator.

2. As an insulator petticoat-guard, a centrally perforated plate with a downwardly-and-outwardly turned drip-lip bounding said perforation, and with a plurality of upwardly-and-inwardly projecting spring fingers formed to embrace the body of an insulator.

3. As an insulator petticoat-guard, a centrally perforated plate downwardly inclined toward its perforation, and with a plurality of upwardly-and-inwardly projecting spring fingers formed to embrace the body of an insulator.

4. As an insulator petticoat-guard, a centrally perforated plate, having a plurality of upwardly-and-inwardly projecting spring fingers formed at its outer edge to externally embrace the body of an insulator.

In witness whereof, I, MINOT K. HOLMES, have hereunto set my hand at Muncie, Indiana, this 10th day of April, A. D. one thousand nine hundred and thirteen.

MINOT K. HOLMES.
